(57) **CLAIM**

The ornamental design for indicia for a package, as shown and described.

DESCRIPTION

FIG. 1 is a perspective view of an embodiment of indicia for a side of a package showing our new ornamental design where the broken lines which define the bounds of the claimed design and illustrate the environmental structure form no part thereof;

FIG. 2 is an elevation view of the embodiment shown in FIG. 1;

FIG. 3 is an elevation view of the embodiment shown in FIG. 1;

FIG. 4 is an elevation view of the embodiment shown in FIG. 1;

FIG. 5 is an elevation view of the embodiment shown in FIG. 1;

FIG. 6 is a plan view of the embodiment shown in FIG. 1; and

FIG. 7 is a plan view of the embodiment shown in FIG. 1. FIG. 8 is a perspective view of an embodiment of indicia for a package showing our new ornamental design where the broken lines which define the bounds of the claimed design and illustrate the environmental structure form no part thereof;

FIG. 9 is an elevation view of the embodiment shown in FIG. 8;

FIG. 10 is an elevation view of the embodiment shown in FIG. 8;

FIG. 11 is an elevation view of the embodiment shown in FIG. 8;

FIG. 12 is an elevation view of the embodiment shown in FIG. 8;

FIG. 13 is a plan view of the embodiment shown in FIG. 8; and,

FIG. 14 is a plan view of the embodiment shown in FIG. 8. The broken lines in the Figures form no part of the claimed design.

1 Claim, 6 Drawing Sheets
